UNITED STATES PATENT OFFICE.

ALBERT L. GALUSHA, OF SHARON, MASSACHUSETTS.

GAS PRODUCER.

Application filed May 28, 1920. Serial No. 364,860.

To all whom it may concern:

Be it known that I, ALBERT L. GALUSHA, a citizen of the United States of America, residing at Sharon, in the county of Norfolk and State of Massachusetts, have invented certain new and useful Improvements in Gas Producers, of which the following is a full, clear, and exact description.

In the art of making producer gas, as it is termed, it has heretofore been universally customary to employ some form of apparatus similar in its general construction to an ordinary furnace, and in which provision is made for maintaining a draft up through a grate and a superincumbent mass of fuel. Such forms of apparatus have their practical limitations, for example, it is not possible, or at least practicable, to use very low grade, or very finely divided fuel, the latter because of the difficulty of maintaining the draft up through grate and fuel, nor can such material be employed as will cake under the action of heat and thus solidify the mass of fuel, nor liquid fuel, such as bye product tar without great trouble and expense.

Aside from these limitations the apparatus heretofore used requires much head room and space, as there must be ample means and room provided for supplying fuel and withdrawing ash, for poking and cleaning the fire, and for other like purposes. All of these well recognized objections have led me to devise and design a form of gas producer of this kind which wholly avoids them.

According to my present invention I dispense with a grate, and in its place I use a substantially air-tight traveling platform or support for the fuel, in the nature of a belt, which receives at one end of the furnace the fuel in regulatable quantity and carries it through the furnace continuously, and the latter is so constructed as to afford but little head room in the combustion chamber whereby the air or air and steam supplied at one end of the fuel bed may be drawn or forced over the surface only of the fuel, and carries off the unconsumed gaseous products to a receiver or to any device that may be provided for its immediate use.

The above, in general terms, defines the nature of my improvement, but for practical use certain accessories are required, the nature and purpose of which may best be gathered from the description of the draw-

ings illustrating the apparatus which follows:

In these drawings Fig. 1 is a vertical longitudinal section of the complete apparatus, and

Fig. 2 is a view partly in cross section and partly in elevation of the same, on the line 2—2 of Fig. 1.

The part of the apparatus which may be designated as the furnace is built in any preferred and known manner, preferably and chiefly of fire brick with a brick ceiling 1 and vertical walls 3 overlaid with heat insulating material 4. The furnace is of substantially greater length than width, and in close proximity to the upper top wall 1 is a traveling belt composed of closely fitting slabs or tiles 5, properly hinged or joined together and supported by two drums, or sprocket wheels 6 and 7.

Immediately under the edges of this belt and secured to the side walls of the furnace are angle irons 8 forming troughs which are filled with coal dust or other finely divided material which not only serves to maintain an air-tight joint between the belt and the side walls, but to lubricate the surface over which the belt travels. At one end of the furnace is a shaft 9 carrying outside the furnace wall a sprocket wheel 10 by means of which motion at the proper and desired speed is imparted to the belt 5.

At the rear of the structure is a fuel feed pipe 11 through which fuel is fed into a compartment 12, sloping towards the bottom under which travels the belt. A sliding and adjustable plate 13 is used to regulate the height of the passage into the furnace and hence the amount of fuel which at any given speed of the belt is carried into the furnace. Alongside this feed compartment is a gas compartment 14 with a delivery pipe 15 and as the gas enters this compartment the ash and impurities have an opportunity to settle and not pass off through pipe 15 to the scrubber or other devices that may be used to clean, store or burn it.

At the forward end of the furnace is a pipe or any number of pipes 16 through which water, steam, tar or other substances may be delivered on to the traveling bed of fuel to promote, retard, or increase the combustion and the generation of gas. There is also a hinged lid 17 that intercepts the dust which may tend to rise from the ash as it is delivered from the fuel bed.

The manner of using and the mode of operation of this apparatus is as follows: The fuel to be used is supplied, as explained, to the compartment 12 and the belt started in motion. When the fuel has reached the forward end it is ignited by a charcoal fire, gas flame, or otherwise, and air forced in at the forward end or drawn off from the rear end of the combustion chamber. The heat of this fire volatilizes the fuel in the bed, and as the latter is converted into gas the belt is set in motion to deliver fresh fuel only so fast as that in the combustion chamber has been converted or consumed. The product, producer gas, passes into the chamber 14 and off by pipe 15, and it will be noted that no air or gas in this product has passed up through the fuel bed, but over it in the combustion chamber of limited capacity.

The richness of the product may be determined by the regulated speed of the belt, as will be understood by those skilled in the art. If desired the speed of the belt may be such as to produce coke and gas, the former being delivered from the traveling belt and falling into the pit below from which it may be readily removed. The entire operation of the apparatus is automatic, and hence its operation may be conducted at the minimum of expense.

What I claim as my invention is—

1. In a gas producer, the combination with an elongated combustion chamber of limited sectional capacity, of an imperforate traveling fuel support traversing the same from end to end, means for depositing fuel thereon at the rear end in regulable amount, and means for conveying off the gases which are driven off from the fuel bed by the heat developed by the combustion of a portion of the fuel at the forward or delivery end.

2. In a gas producer, the combination with an elongated combustion chamber of limited sectional capacity, of an imperforate or air-tight fuel support, means for causing said support to travel through the chamber from end to end of the same, means for depositing fuel thereon at the rear end, means for developing and maintaining a high temperature over the top of the fuel bed, and means for conveying off the gases driven off therefrom.

3. In a gas producer, the combination with

a combustion chamber of limited sectional capacity and substantial length, of a traveling belt traversing the same from end to end and composed of heat resisting material and substantially air-tight, constituting a fuel support, means for depositing fuel thereon in regulable quantity, means for developing and maintaining a high temperature over the top of the fuel bed, and means for conveying off the gases driven off therefrom by such temperature.

4. The combination with a combustion chamber of great length but limited height, of a traveling belt constituting a fuel support and traversing the chamber from end to end, means for introducing substances into the forward end of the chamber for promoting or retarding combustion at that point, and means for conveying off the gases produced by the high temperature due to such combustion acting upon the fuel bed.

5. The combination with a combustion chamber of great length but limited height, of a belt movable through the chamber and constituting an imperforate fuel support, of shelves along the sides of the chamber and in close proximity to the under surface of the belt for containing a powdered substance to form an air seal.

6. The combination with an elongated combustion chamber of an infusible fuel support mounted to travel through said chamber which is imperforate or air-tight, and angle irons secured to the chamber walls under the edges of said belt and containing a suitable material to form an air seal between the belt and the chamber walls.

7. The combination with a combustion chamber of relatively great length and of limited height, of drums or sprockets at its ends, an endless belt of heat resisting material and without air passages mounted on said sprockets and constituting a fuel support which is adapted to travel through the chamber and convey fuel through the same, pipes for introducing into the forward end of the chamber over the fuel on said belt substances to promote or retard the combustion, and pipes for conveying off the gases generated in the chamber.

In testimony whereof I hereto affix my signature.

ALBERT L. GALUSHA.
